UNITED STATES PATENT OFFICE.

DAVID HARRISON SNEED, OF STONEWALL, OKLAHOMA.

MACHINE FOR SHARPENING PLOWSHARES, DISKS, &c.

No. 876,742.

Specification of Letters Patent.

Patented Jan. 14, 1908.

Application filed June 28, 1907. Serial No. 381,245.

To all whom it may concern:

Be it known that I, DAVID HARRISON SNEED, a citizen of the United States, and resident of Stonewall, in District 16, Oklahoma, have invented an Improvement in Machines for Sharpening Plowshares, Disks, &c., of which the following is a specification.

My invention is an improvement in shares for sharpening plow shares, harrow disks, and the like, and for rolling out plates and training shoes; and the invention consists in certain novel constructions and combinations of parts as will be hereinafter described and claimed.

In the drawings, Figure 1 is a side elevation of a machine embodying my invention, the swinging carrier for the work holder being shown raised in dotted lines. Fig. 2 is a top plan view of the machine. Fig. 3 is a front elevation of the machine looking at the rollers, the work holder being broken away. Fig. 4 is a detail perspective view illustrating the swinging carrier and work holder, together with the frame bars to which the swinging carrier is pivoted. Fig. 5 is a perspective view of the bearing frame for the adjustable roller, showing the same in connection with the eccentric and the shaft therefor, whereby the said bearing frame may be raised and lowered, and Fig. 6 is a detail view illustrating the bearing for the lower shaft.

In the construction shown, I support the several parts on the bed plate A having bearings B, in which is journaled the drive shaft C provided with tight and loose pulleys at D, and also having a pinion E which meshes with a gear F on a roller shaft G, preferably the lower stationary roller H as shown.

This shaft G has a pinion I which meshes with a pinion J on a roller shaft K of the roller L, the latter being adjustable toward and from the roller H by the means presently described.

The shaft K is loosely mounted at its rear end in a bearing M, while its front end is mounted in a bearing N in the upper end of the bearing frame O, which bearing frame may be raised and lowered by the means presently described to adjust the roller L toward and from the roller H as may be desired in the operation of the invention.

In the construction shown, the bearing frame O is provided at its lower end with a depending portion 1 having a circular bearing in which fits an eccentric 2 on a shaft 3

journaled to the main frame, and this shaft may be turned to operate by its eccentric to raise and lower the bearing frame. The shaft has a handle 4 by which it may be turned, and a pawl 5 supported on the main frame and engaging with notches or serrations 6 operates to hold the shaft in any desired adjustment. By this means, the bearing frame O may be raised and lowered as desired.

In the construction shown, the bearing frame O is provided with side bars 7 which extend from its lower portion 1 upwardly on opposite sides of the rollers L and H, and support at their upper ends the bearing for the upper roller L, as best shown in Fig. 3 of the drawings.

The main frame is provided with bars 8 which project upwardly along the opposite sides of the roller shafts, to a point above the upper shaft, and afford a pivotal support at 9 for the swinging carrier P for the work holder. This carrier P is made in sections 10 and 11, adjustable longitudinally relative to each other, and arranged to be secured in different adjustments by the nut 12, turning on a screw 13 to bind the sections together, as will be understood from Fig. 4 of the drawings. The front section 11 is provided with a depending portion 14, to which is pivoted the work holder 15. This holder 15 is pivoted at its upper end to the depending portion of the carrier, is provided below its pivot with the outwardly projecting arm 16, on which the weight 17 may be secured so it can be adjustable along the arm, it may be by threading the arm and screwing the weight thereon as shown, and below this arm the work holder supports the work. Manifestly, the work may be adapted for the particular kind of work it is designed to hold. That shown is adapted to receive harrow disks, and its end is threaded, and the harrow disk is slipped up over the threaded portion of the work holder and a nut 18 is screwed on the work holder up against the harrow disk pressing the same against a shoulder provided for the purpose, as shown. The lever arm with the weight 17 operates automatically to hold the work to the rolls or dies between which the work is held in the operation of the machine. Manifestly, these dies may be varied and different sets applied for different classes of work.

A spring Q operating between the front bearings of the fixed and movable roll shafts,

is arranged to spread the rollers or dies when the eccentric for operating the bearing frame is turned by its raising of its lever.

In the operation of the machine, motion is given to the shafts and the rolls or dies thereon by the gearing before described, and by means of the eccentric operating upon the bearing frame I am enabled to adjust the pressure on the dies instantly to any desired degree.

I claim:

1. A machine substantially as herein described, comprising a main frame, a drive shaft, a roller shaft geared with the drive shaft, and having a pinion, a roll or die on said shaft, a second roller shaft having a pinion meshing with that of the first said shaft, and provided with a roll or die coöperating with that on the first shaft, a bearing for the rear end of the second shaft, a bearing frame having at its upper end a bearing for the front end of the second shaft, said bearing frame having side bars extending down on opposite sides of the shafts, and provided at its lower end with a portion having an opening for an eccentric, an eccentric in said opening, and means for turning the eccentric whereby the operation of the eccentric will move the movable die toward and from its mate.

2. A machine substantially as described,

comprising a main frame, opposing rolls and their shafts, a work holder, a carrier supporting said holder at one end, and frame bars secured to the main frame and projecting upwardly along the opposite sides of the roll shafts, and affording a pivotal support at their upper ends for the swinging carrier, substantially as set forth.

3. The combination with a main frame, and the roll shafts, of a swinging carrier pivoted at one end to the frame, and a work holder having a pivotal connection with the other section of the carrier and adapted to support the work to be operated upon, and a weighted arm in connection with said work holder, whereby to hold the work to the rolls or dies, substantially as set forth.

4. The combination of the main frame having bearings for a roller shaft, a roller shaft journaled in said bearings, a second roller shaft operating with said first shaft, bars extending from the main frame upwardly on opposite sides of the said shafts, a swinging carrier pivoted at one end to the upper ends of said bars, and work holding devices supported by said swinging carrier, substantially as set forth.

DAVID HARRISON SNEED.
